METHOD OF SETTING TYPE AND
MECHANISM THEREFOR

John L. Weigand, Dayton, Ohio

Application February 3, 1938, Serial No. 188,535

5 Claims. (Cl. 101—396)

The object of my invention is to provide a novel way and means of forming a line of type for individual foundry type high type, which is justified and held together as a unit ready for installation into a chase.

It has been considered necessary to form a casting from type in order to serve the same purpose as is served by my invention. My novel practice, however, does not require this, utilizes foundry type, and justifies the line before retaining it together mechanically as a unit, for use in printing.

Briefly I provide for means in the bodies of the type, a spacing quad which is expansible when compressed, and a holder which utilizes this expansibility to retain the type in a portable line, ready for installation into a chase. Also the type can be removed from the assembly, for assorting it for re-use without any difficulty, and without necessity of modifying the type structure adapted to present sorting devices.

Among other things I provide a type receiving holder which is combined preferably with a justifying mechanism, and preferably also a mirror to make the type laying easy. Also I provide a holder which seats in a countersink in each type body and does not project beyond the type at the ends of the line into which holder the type expands and thus frictionally is retained.

I accomplish my object more specifically by that practice and structural arrangement to be hereinafter illustrated in the drawings and described with reference to a single example. The novelty inherent in my invention will be set forth in the claims that follow, to which reference is hereby made.

In the drawing:

Figure 1 is a perspective of a piece of foundry type altered to use according to my invention.

Fig. 2 is a quad adapted to use in my invention.

Fig. 3 is a holder, also adapted for said use.

Figs. 4 and 5 are side elevations of a line of type with the holder about to be applied, and with the holder in position as it is first applied.

Fig. 6 is a perspective showing the line of type in the final position of being gripped fast by the holder due to expansion.

Fig. 7 is a perspective of an assembling board and justifier.

Fig. 8 is a view of a modified end plate for the holder.

Fig. 9 is a section on the line 9—9 of Fig. 2, showing the preferred form of quad in longitudinal section.

It will be more readily understandable to de-

scribe the mechanical structure employed by me beginning with the type. I propose to use the regular form of foundry type having the type high body 1 and the type face 2. The usual groove 3 whereby the type face is oriented and whereby the type may be later assorted mechanically, may be provided, as usual. In addition I provide for an assembling groove 4 in the proper orientation to the type face, i. e., on that portion of the type body which will be uppermost when printing. The grooves 4 are uniform in position and of uniform dimensions for each type used.

The simplest form of compressible and expansible quad which I employ is one having side plate 5, 5 of thin metal of size and shape of the type bodies, so as to facilitate handling. Between the plates is located a strip of rubber or other compressible and expansible material 6. The quads will also have like grooves 7, corresponding to the grooves 4.

Referring now to Fig. 4, I have shown a line of type 1, 2, set up with the quads 5, 6, and ready for justifying. Fig. 5 shows this line of type compressed to justify it, i. e., to impart the correct length to the line, although as shown, and as practiced by me this justification is to a dimension slightly less than the desired length of the line. In Fig. 4, the holder is shown separated, and in Fig. 5 as it is slipped over the justified line 30 of type.

The holder consists of a bar 8, which will fit snugly into the grooves 5 of the type and 7 of the quads. On the ends of this holder will be plates 9 which are preferably of substantially the dimension of the type itself, although they might be somewhat smaller. They should not be larger.

When this holder is slipped down over the line of type with the bar 8 snugly engaging and thus countersunk into the type and quad bodies, as illustrated in Fig. 5, the outer faces of the type extremities of the line will not touch the end plates 9. When the line of type is released from the grip of the justifying means, the quads will endeavor to expand and this will result in the type being gripped by the end plates. As shown in Fig. 6, I then have a portable line of type made up of foundry type, capable of any use to which a cast line of type can be used, but which can be disassembled by pulling away the holder.

The holders will be made to dimensions which will be exactly correct for the final line justification or dimension. If the justifying device has to be cleared by the holders it will be the best practice to form a groove 10, in each of the end

plates whereby the end plates will clear the jaws of the justifying device.

I have shown a simple assembling board in Fig. 7. The base of the board supports a pair of movable jaws 11, which will be movable to and from each other by some suitable mechanism (not shown). These jaws operate through a slot 12, in a slanting back 13 against which the type is laid. A bottom ridge 13a is located at right angles to the slanting back, on which the type is supported when being laid. If desired a mirror 14 is erected above the back 13, in order that the type setter can see the type as he lays them, with their printing faces slanted away from him. 15 Also on the back board I will preferably locate a scale 15, the calibrations being such that the type setter can bring his line of type to approximately the correct dimension.

Proceeding with the use of the assembling board, the operator will spread the justifying jaws 11, and commence placing the type and quads on the bottom ridge or supporting ledge, resting against the back. He will use the scale for his starting and end of the line approximately 20 a little beyond the necessary line length for the ultimate printing. He will then bring the jaws together, watching the scale so that the type will be justified by compression of the quads to slightly less than the dimension for the printed 25 line, which will also be slightly less than the dimension of the holder which he will employ. He then pushes the holder into place and releases the justifying jaws. In this operation the slotted end plates are of advantage because the holder 30 can be put at least partially in place before the pressure is relaxed. In case the type does not spring out immediately due to expansion of the quads this slot will not be necessary.

The type will in any event expand to the exact 40 line dimensions as defined by the spacing of the holder end plates, and will furthermore stay in position gripped by the holder, due again to the functioning of the quads. It can then be removed and moved for location in a chase, or for 45 any printing operation, without coming apart or without losing line justification or alignment. The holder is entirely out of position where any of its edges will print, and the rubber filling of the quads is less than the dimension of the 50 side plates of the quads so that it will not be squeezed out into printing position as a result of compression.

When the printing is accomplished for which the type was set, the units can be removed from the printing device, the holders pulled away and 55 the type sorted into kinds.

The simplicity of this practice in hand type

setting to accomplish the same objects as line cast type operations is apparent without further discussion. The equipment is cheap, the grooving of the type an operation which can be performed in the same manner as the present 5 grooving without additional foundry operations.

Instead of justifying by the use of a scale, there might readily be applied an adjustable mechanism whereby the justifying jaws would come to a single position when forced toward 10 each other dependent upon some pre-setting of the mechanism. The type could be set in some other form of device so long as the justification could be applied to them in a manner permitting the application of the holder. 15

Having thus described my invention, what I claim as new and desire to secure by Letters Patent, is:

1. A method of type setting using foundry type which consists in assembling and justifying a line 20 of type employing compressible and expandable quads, and then applying a holder to the type, so as to snugly engage grooves in the type and abut the ends of the type in the line.

2. A method of type setting using foundry type 25 which consists in assembling and justifying a line of type employing compressible and expandable quads, and then applying a holder to the type, so as to snugly engage grooves in the type and abut the ends of the type in the line, the type 30 being first justified to smaller than final justified length so as to expand within the holder between the end plates.

3. For use in the practice of justifying a line 35 of type, a type setting board having a grooved slanting wall against which type is to be rested, justifier jaws projecting through said groove, and a ledge substantially at right angles to the wall on which the type are supported.

4. For use in the practice of justifying a line 40 of type, a type setting board having a grooved slanting wall against which type is to be rested, justifier jaws projecting through said groove, and a ledge substantially at right angles to the wall 45 on which the type are supported, said wall being surmounted by a mirror for viewing the type while setting the same.

5. For use in the practice of justifying a line 50 of type, a type setting board having a grooved slanting wall against which type is to be rested, justifier jaws projecting through said groove, and a ledge substantially at right angles to the wall on which the type are supported, said wall having a justifying calibrated scale thereon, whereby the justification can be made. 55

JOHN L. WEIGAND.
